UNITED STATES PATENT OFFICE

RAYMOND S. HINTZE, OF CHICAGO, ILLINOIS

DISPLAY RACK AND STAND

Application filed April 18, 1929. Serial No. 356,172.

My invention relates to improvements in display racks and stands, and it consists in the combinations, constructions, and arrangements herein described and claimed.

5 An object of my invention is to provide a display rack and stand which has novel means for supporting a plurality of racks or casings so that they may be moved in a circuitous path or moved with respect to their 10 supporting member and with respect to each other so that the cards displayed therein may be readily viewed.

A further object of my invention is to provide a device of the type described which 15 has novel means for supporting the cards so that the cards will not in any way be soiled or destroyed.

A further object of my invention is to provide a device of the type described which 20 has novel means for positioning the supply of cards in close proximity to the card in the display section.

A further object of my invention is to provide a device of the type described which 25 has adjustable partitions which may be positioned to receive cards of various sizes.

A further object of my invention is to provide a device of the type described which 30 has novel means for opening the cards of the booklet type so that the buyer may view the inner portion thereof without handling the card.

Other objects and advantages will appear 35 in the following specification, and the novel features of the invention will be particularly pointed out in the appended claims.

My invention is illustrated in the accompanying drawings, forming part of this application, in which

40 Figure 1 is a perspective view of my device,

Figure 2 is a detail view of the supporting means,

Figure 3 is a longitudinal sectional view 45 of one of the casings, showing the display door partially opened,

Figure 4 is a section substantially along the line 4—4 of Figure 3,

50 Figure 5 is a detail view of the card-holding means, and

Figure 6 is a section substantially along the line 6—6 of Figure 5.

In carrying out my invention, I provide a base 1 which has a hollow neck portion 2 arranged to receive a reduced portion 3 of a supporting shaft 4. An annular recess 5 is disposed in the reduced portion 3 and arranged to receive the inner end of a set screw 6 which allows the shaft and the reduced portion to rotate but holds them against 60 vertical displacement.

A supporting table or member 7 is disposed concentric with the shaft 4 and the reduced portion 3, and is provided with upwardly extending pivot pins 8 disposed at 65 spaced-apart positions adjacent the peripheral edge thereof. A bearing 9 is disposed between the supporting member 7 and the hollow neck portion 2 of the base 1. A head portion 10 is disposed upon the upper end 70 of the shaft 4 and is provided with pivot screws 11 which are in alignment with the pivot pins 8 upon the supporting member 7.

A plurality of display casings 12 is disposed between the supporting member 7 and the head portion 10 and is pivotally held in place by the pivot pins 8 and the pivot screws 11 which extend through openings in the bottom 13 and the top 13^x, respectively, of the casings. The casings are provided with side 80 walls 14 and 15 which have inwardly stamped lip members 16. A central vertical partition 17 is disposed in the casing and is provided with a plurality of stamped-out lip portions 18, some of which are disposed upon one side 85 thereof and the others disposed upon the opposite side thereof. A plurality of shelves 19 having downwardly extending flanges 20 is provided and arranged to be disposed between the partition 17 and the side walls 14 90 and 15. The flanges 20 engage with the stamped-out portions 16 and 18, and when thus positioned form a plurality of card or booklet-receiving compartments 21.

The side wall 15 is provided with flanges 95 22 for receiving a transparent member 23 and holding the transparent member 23 at a spaced-apart position from the side wall 15. An article-supporting member 24 is arranged to be disposed between the wall 15 and the 100

transparent member 23. Spaced-apart supporting strips 25 are secured to the member 24 at spaced-apart positions for supporting the articles or cards indicated at 26. Retaining strips 27 are secured to the supporting strips 25 so as to provide openings or spaces 28 therebetween for receiving holding members 29. The vertically extending portions of the holding members 29 are arranged to extend through the openings 28 and hold the upper portions of the cards 26, whereas the horizontally extending portions of the holding members 29 are arranged to hold the lower portions of the cards 26.

The side wall 14 is provided with a flange 30 which is arranged to receive a booklet-supporting member 31. Booklets 32 have their back portions secured to the supporting member 31 by the same means as indicated in Figures 5 and 6 for securing the cards 26 in place. A display door 33 is hingedly secured at 34 to the side wall 14 and is provided with a cord or rod 35. The covers or front portions of the booklets 32 are held adjacent the display door 33 by means of the cord 35.

A casing door or cover 36 is hingedly secured to the wall 15 and is normally held in closed position by means of a spring 37.

From the foregoing description of the various parts of the device, the operation thereof may be readily understood. The device may be positioned at any desired location so that the supporting member 7, together with the casings 12, may be freely rotated thereupon. Handles 38 are carried by the supporting member 7 and extend radially therefrom at positions between the casings 12. The customer desiring to purchase a card or booklet may rotate the supporting member 7 by the aid of the handles 38 until the casing containing the desired group of cards or booklets is brought into view. The cards 26 may be readily viewed through the transparent member 23. The stock of cards may be contained in the compartments 21 which are nearest the cards positioned upon the card-supporting member 24. By opening the door or cover 36, the desired number of cards may be readily removed therefrom.

Let us assume that the customer wishes to purchase one of the booklets. The cover or front portion of the booklet may be readily viewed through the transparent door 33. To view the inner portion of the booklet, the customer may open the door 33, and in so doing the cord 35 will open the booklets, displaying the interior thereof to the view of the customer. In this manner the cards and booklets may be readily viewed without the necessity of the customer or the salesman touching them and thus soiling them.

Furthermore, the means indicated in Figures 5 and 6 for holding the cards or booklets in their respective positions in engagement with their respective supporting mem-

bers 24 and 31 makes it possible to hold the cards and booklets in place without soiling them so that they may be removed and sold if so desired. The pivotal connection of each casing to the supporting member 7 and the head portion 10 permits each casing to be moved so that the cards and booklets may be more readily viewed. The compartments 21 are provided for the booklets in their respective orders, the same as the compartments for the cards.

A retaining member 39 is U-shaped in cross section and is arranged to be disposed upon the upper end of the transparent member 23 for holding the card-supporting member 24 in place.

I claim:

1. A device of the type described comprising a base, a supporting member rotatably mounted upon said base, a plurality of display casings, means for pivotally securing said casings to said supporting member whereby said casings may be pivotally moved with respect to said supporting member and moved in a circuitous path with respect to said base, card-supporting members, means carried by said casings for receiving said card-supporting members, booklet-supporting members, means carried by said casings for receiving said booklet-supporting members, means for removably securing a plurality of booklets to said booklet-supporting members, doors for said casings, and means carried by said doors for opening said booklets when said doors are opened.

2. A device of the type described comprising a casing, a booklet-supporting member, means for removably securing a plurality of booklets to said booklet-supporting member, means carried by said casing for receiving said booklet-supporting member, a door for said casing, and means carried by said door for opening said booklets when said door is opened.

3. A display rack comprising a base, a supporting member rotatably mounted upon said base, a plurality of display casings, means for pivotally securing each of said casings to said supporting member, means carried by each casing for supporting a plurality of booklets, a transparent door for each of said casings for viewing the exterior of the booklets, and means carried by the door for opening the covers of the booklets when the door is opened whereby the interior of the booklets may be viewed.

4. A display rack comprising a base, a supporting member rotatably mounted upon said base, a plurality of display casings, means for pivotally securing said casings to said supporting member for movement relative thereto, means carried by the casings for supporting the body portions of a plurality of booklets within the casings, a door for each of said casings pivotally secured to the cas-

ing, and means carried by the door and movable therewith for opening the covers of the booklets within the casing simultaneously whereby the interior of the booklets may be viewed.

5 Signed at Chicago, in the county of Cook and State of Illinois, this 10th day of April, A. D. 1929.
